(57) **CLAIM**

The ornamental design for a ball massager with cup, as shown and described.

DESCRIPTION

FIG. 1 is an upper perspective view of the ball massager with cup showing my design in an assembled configuration with the ball component partially housed in the cup component; FIG. 2 is an upper perspective view of the ball component thereof, showing the ball component outside of the cup component and the cup component removed for ease of illustration of the ball component;

FIG. 3 is an upper perspective view of the cup component thereof, showing the ball component outside of the cup component and the ball component removed for ease of illustration of the cup component;

FIG. 4 is a top plan view of the ball component only;

FIG. 5 is a front elevation view of the ball component only, the back elevation view being identical thereto;

FIG. 6 is a side elevation view of the ball component only, the opposite side elevation view being identical thereto;

FIG. 7 is a bottom plan view of the ball component only;

FIG. 8 is a top plan view of the cup component only, the back elevation view being identical thereto;

FIG. 9 is a front elevation view of the cup component only, the back elevation view being identical thereto;

FIG. 10 is a side elevation view of the cup component only, the opposite side elevation view being identical thereto; and,

FIG. 11 is a bottom plan view of the cup component only.

The surface contours are shown by stippling on the surfaces.
